UNITED STATES PATENT OFFICE.

HENRY W. PLEISTER, OF WESTFIELD, NEW JERSEY, ASSIGNOR TO HENRY B. NEWHALL.

BOLT-ANCHOR.

1,267,903.

Specification of Letters Patent. Patented May 28, 1918.

Original application filed September 20, 1916, Serial No. 121,105. Divided and this application filed September 18, 1917. Serial No. 191,920.

To all whom it may concern:

Be it known that I, HENRY W. PLEISTER, a citizen of the United States, residing at Westfield, in the county of Union and State 5 of New Jersey, have invented certain new and useful Improvements in Bolt-Anchors, of which the following is a specification, taken in connection with the accompanying drawings.

10 This application is a division of my co-pending application, Ser. No. 121,105, filed Sept. 20, 1916.

My invention relates to bolt anchors and more particularly to a bolt anchor which 15 has a great holding capacity and yet one which will not crack a wall, a partition, a block of marble, stone or any other material in which it may be desired to use my bolt anchor.

20 The common form of bolt anchors are expanded by having the expanding member, the screw or bolt, move down an inclined surface which extends approximately from one end to the other, reaching its nearest 25 approach to the axis of the anchor at the end which is farthest embedded in the wall, block or other material. This causes the maximum expansion to be at the very end of the bolt anchor. This makes it impossible 30 to use the ordinary common form of expansion bolt in many locations.

My expansion bolt removes the point of maximum expansion from the end of the bolt and insures a gradually lessening grip 35 and wedging action from that point to the end of the bolt.

My present invention relates more particularly to that class of bolt anchors known as anchors, or ductile anchors, or lead anchors, 40 or screw anchors, in which the material of the anchor is some relatively soft metal, such as lead or an alloy, in which the screw cuts its own coöperating screwthreads.

My invention further relates to certain 45 details of construction which will be described in the specification and pointed out in the claims.

I have shown in the accompanying drawings several illustrative embodiments of my 50 invention but of course it is to be understood that my invention is not to be confined simply to the forms illustrated. In these drawings the same reference numerals refer to similar parts.

55 Figure 1 is a longitudinal vertical section

of my bolt anchor shown as a ductile anchor, lead anchor, or screw anchor.

Fig. 2 is a vertical section of my anchor mounted in a comparatively shallow block of marble, stone or similar material. The 60 work supported is shown in section and the wood screw in side elevation.

Fig. 3 is a longitudinal vertical section of my anchor provided with a weakening portion.

65 Fig. 4 is a longitudinal vertical section of the anchor shown in Fig. 3 showing it expanded and coöperating with the support to hold the work.

In the illustrative embodiments of my invention 1 is an anchor having a collar 2 and two tines 3 and 4 and an axial bore 5 which has a tapered portion 6 which reaches its nearest approach to the axis of the anchor at 7, and then recedes or flares from that 70 point to the end 8 of the anchor forming a flaring surface 9. Ordinarily these anchors, or ductile anchors, or lead anchors or screw anchors 1 as they are called in the trade, are used for lighter work than are lag shields. 80 The expanding member is usually a wood screw 10 which cuts its own coöperating screwthreads in the anchor as it is screwed home.

It is well known that in thin walls, or 85 thin partitions, or thin slabs of stone, marble, slate or similar material 11, the ordinary form of lead anchor often cannot be used for the reason that the maximum expansion would occur at the points 12, 12 90 which will cause the surface 13 of the slab of marble, stone, slate, the partition or other support 11 to become cracked, chipped or otherwise marred.

By my invention I avoid the cracking, or 95 marring or breaking of the slab of marble, stone, slate or wall or other support 11 by removing the maximum strain and wedging stresses from the points 12, 12 to a point removed from the end 8 of the anchor and far 100 enough away from the surface 13 so as to bring the point of maximum expansion well within the body of the slab of marble, stone, slate or wall or partition 11.

In the operation of my invention, Fig. 2, 105 the hole 14 is formed leaving a comparatively thin portion 15. The ductile anchor 1 is then inserted and the work 16 will be snugly held to the face 17 of the slab of stone, marble, slate or the partition or other 110

support 11 by means of the wood screw 10 which will cut its own coöperating screw-threads in the body of the anchor as it is screwed along the axial inclined bore 6, the maximum expansion being exerted substantially at the points 18, 18, well within the slab of marble, stone, slate or wall, partition or other support and removed from the thin portion 16. From the points 18, 18, Fig. 2, to the end 8 of the anchor the gripping action will gradually lessen so that at the very end 8 of the anchor no strains will be exerted which will cause a fracture, crumbling, or marring of the face 13 of the support 11 whatever material it may be formed of.

To make the action even more delicate and to insure that no possible excessive strains shall be caused to be exerted near the end of the anchor I form my anchor 19, Fig. 3, with weakening portions 20, 20. In this form I also employ a collar 21, tines 22, 23, an inclined axial bore 24, reaching its nearest approach to the axis of the anchor at the point 25 and then flaring to the end 26 of the bolt anchor forming a flaring surface 27, the same as in the other form previously described.

When the wood screw 10, cutting its threads in the body of the anchor 19, passes the point 25 which is the point of minimum diameter of the axial bore 24, the weakened portions 20, 20 will permit the end portions 28, 28 to move slightly with relation to the other portions of the anchor and tend to cause the two sides of the valleys 29, 29 to move apart or open, Fig. 4, should by any circumstances any considerable strain be exerted upon the portions 28, 28 which might have a tendency to crack or injure the surface 13. These valleys 29 are preferably formed by casting them within the anchor.

In all figures of the drawings the inclined and flaring surfaces, as well as the gripping action of the anchor, are somewhat exaggerated for purposes of clearer illustration.

It is also apparent that different thicknesses of work 16 can be held by the same anchor without the wood screw 10 binding

before it has snugly secured the work to the 50 face 17 of the slab of marble, stone, slate or wall or support 11.

Having thus described this invention in connection with illustrative embodiments thereof to the details of which I do not 55 desire to be limited, except as required by the scope of the appended claims, what is claimed as new and what is desired to secure by Letters Patent is set forth in the appended 60 claims.

What I claim as my invention and desire to secure by Letters Patent is:—

1. The combination of a ductile anchor provided with an axial bore of minimum diameter between its ends said bore flaring 65 from its minimum diameter toward each end, and a screw to directly engage both of said flaring surfaces to cut its own female threads to expand the ductile anchor.

2. The combination of a ductile anchor 70 provided with an axial bore of minimum diameter between its ends, said bore flaring from its minimum diameter toward each end, said ductile anchor being provided with one or more weakening portions and a screw 75 to directly engage both of said flaring surfaces to cut its own female threads to expand the ductile anchor.

3. The combination of a ductile anchor having a collar, tines, and an axial bore 80 having its minimum diameter between the ends of the anchor and flaring from its minimum diameter toward each end, and a screw to directly engage both of said flaring surfaces to cut its own screw threads and expand the ductile anchor.

4. The combination in a ductile anchor of a collar, tines, an axial bore having its minimum diameter between the ends of the anchor and flaring from its minimum diameter toward each end, said anchor being provided with one or more weakening portions adjacent to the minimum diameter of the axial bore. 90

HENRY W. PLEISTER.
